UNITED STATES PATENT OFFICE.

CHARLES EUGÈNE GUYE, OF GENEVA, SWITZERLAND, ASSIGNOR TO SOUTHERN POWER COMPANY, OF CHARLOTTE, NORTH CAROLINA, A CORPORATION OF NEW JERSEY.

STABILIZING MEANS FOR ELECTRIC-ARC FURNACES.

1,109,330.

Specification of Letters Patent

Patented Sept. 1, 1914.

Application filed January 8, 1912. Serial No. 670,027.

To all whom it may concern:

Be it known that I, CHARLES EUGÈNE GUYE, a citizen of the Republic of Switzerland, residing at Geneva, Switzerland, have 5 invented new and useful Improvements in Stabilizing Means for Electric-Arc Furnaces, of which the following is a specification.

It is old to place a self-induction, called 10 a reaction, coil, in series, for the purpose of rendering voltaic arcs stable, particularly when they are fed by alternating currents. This coil generally comprises an iron core, usually divided and surrounded by a winding 15 through which the current flows; such is the case particularly with furnaces designed for the production of oxids of nitrogen used in the manufacture of synthetic nitric acid.

20 The object of this invention is a means of rendering electric arcs stable.

It consists essentially in substituting, for 25 reaction coils with iron or magnetic cores, a coil or coils without any iron, consisting of a copper winding; suitably insulated; this copper winding may be made in any suitable form, as a blade, a strand, a tube, etc., of copper. There may be one or more such coils, according to the electrical arrangements 30 of the circuit in which the arcs to be rendered stable, either connected in series or in parallel, or even in series-parallel. If currents of great intensity are to be used, the coils may be placed in an oil cooling bath, suitably cooled in the usual way; the 35 coil may also be made with sufficient spaces between its convolutions to enable the copper to be cooled by a current of air. Practical study of the conditions of operation 40 of these coils without iron has demonstrated that, with equal impedance, they enable a much more perfect stabilization of the arcs to be obtained than where iron is employed for this purpose; also, when the power used 45 in the arcs amounts to about 50 kilowatts, and the reaction coils are of average size, the coils without iron are much more economical than those with iron; their construction is also simpler since the laminated 50 iron cores are eliminated. Finally, when the coils attain average dimensions, the electric energy consumed in the reaction coil without iron is materially less than that consumed in the coils with iron. This

economy in energy results, in a large degree, from the suppression of the voluminous iron cores in which serious losses occur from hysteresis or Foucault currents. In all respects, the employment of coils without iron in electric arc furnaces enables 60 important commercial progress to be obtained, which increases with the power of the arcs to be rendered stable. In particular, this advantage is a maximum when the self-induction coil is given the form which 65 gives the maximum self-induction for the minimum weight in copper. It is especially with furnaces using arcs of great development, such as are employed to produce gaseous chemical reactions that these advantages become considerable. For example, in applying these coils to a large furnace of the Naville, Guye and Guye type, (French Patent No. 350,120, 1894) of a power of 400 to 500 kilowatts, operating 70 under 5500 volts, it has been possible to stabilize with a loss of energy of ten kilowatts, three arcs in series, the total developed length of which was 20 meters.

In the accompanying drawing,—Figure 80 1 is a diagrammatic view illustrating an embodiment of my invention. Fig. 2 is a diagram illustrating the hysteresis loss in magnetic material, and the rate of change of magnetic flux in magnetic material, and also 85 in a magnetic circuit having a permeability equal to one.

In Fig. 1 the reference character E designates electrodes across which an arc is maintained. I designates a reaction coil interposed in the circuit, according to my invention.

The reason why these coils without iron or magnetic cores give ordinarily better results as regards stability may be explained 95 by the following considerations: Considering first an ordinary reaction coil having an iron core. When the winding is traversed by an alternating current, the cycle of magnetization will be represented in Fig. 2, as 100 abscissa, the intensity I of the magnetizing current, as ordinate, the magnetic flux Φ which flows through the iron core. At each instant, the electromotive force of self-induction, which is the principal cause of the 105 stability of the arc, will be proportional to the speed of variation of the flux. Thus it will be seen that it is exactly in the phase

where the intensity diminishes to become zero, that is to say, in the most dangerous phase for the stability of the arc (either on the curves A—O and A'—O') that the 5 average of this variation is least (especially if the iron presents an appreciable coercive force). On the other hand, if the self-induction coil without iron is employed, the 10 variation of the flux, between the same limits of current as in the former case will be represented by the dotted straight line A—O,—A', and it will be seen that the speed of variation of the flux and, consequently, the electromotive force of self-induction, will 15 average greater during all the period which corresponds to the diminution of the intensity of the current (that is to say, during the period unfavorable to the stability of the arc). The stability of the arc will 20 then be considerably augmented by the employment of a coil without iron, as has been

demonstrated experimentally, as above stated.

What I claim is,—

1. The combination with a circuit comprising electrodes between which an electric arc may be produced, and an arc-stabilizing coil of copper wire, free from iron, included in the circuit. 25

2. The combination with a circuit comprising electrodes between which an electric arc may be produced, and an arc-stabilizing coil of copper wire, free from iron, included in the circuit in series with said electrodes. 30

In testimony whereof I have hereunto set my hand in presence of two subscribing witnesses.

CHARLES EUGÈNE GUYE.
